DECORATIVE COVER FOR AN ELECTRIC
LIGHT BULB

David A. Nibur, Los Angeles, Calif.

Application May 6, 1957, Serial No. 46,016

Term of patent 14 years

(Cl. D26—8)

Fig. 1 is a top view of a decorative cover for an electric light bulb illustrating my new design;

Fig. 2 is a side elevational view thereof taken along line 2 of Fig. 1;

Fig. 3 is a side elevational view thereof taken along line 3 of Fig. 1; and

Fig. 4 is a sectional view through a portion thereof, illustrating the surface contour of the center decorative netting.

The sides of the electric light bulb opposite and at 90 degrees from that taken along lines 2 and 3, respectively, in Fig. 1, are the same as that shown in Figs. 2 and 3, respectively.

The broken line showing of a representative electric light bulb is for illustrative purposes only.

I claim:

The ornamental design for a decorative cover for an electric light bulb, substantially as shown and described.
